UNITED STATES PATENT OFFICE

HAROLD WARREN TOOL, OF MURDOCK, NEBRASKA

CORNCOB CONTAINER

Application filed March 25, 1929. Serial No. 349,826.

My invention relates to corn cob containers, its primary object being the provision of a cabinet which is especially adapted for use in kitchens and other rooms for the storage of corn cobs.

5 An important object of the invention is the provision of a cabinet of such design that it is of the maximum convenience in use.

Another object which I have in view is the provision of a cabinet having a separable basket fitting into the cabinet, the basket being light in weight and of a convenient size and shape for transporting the corn cobs from the cob pile to the kitchen.

10 Another object is the provision of a corn cob cabinet which is provided with additional spaces for storing shovels, scoops, dust pans and dust cloths in such a way that they will be entirely out of sight when the cabinet is closed but convenient of access by opening a front door with which the cabinet is provided.

15 It is also my object to provide a closure for the top opening of the cabinet, the closure serving as a table top when it is in closed position and adapted to serve as a table top when in one of its two open positions.

It is, of course, important that the cabinet be so designed that it is attractive in appearance and that it adds to the attractiveness of the kitchen and it is therefore my object to provide such a design.

Having in view these objects and others which will be pointed out in the following description, I will now refer to the drawings, in which

20 Figure 1 is a view in perspective of the cabinet with all of the closures in closed position and showing in dotted lines the inclined wall.

Figure 2 is a vertical sectional view from front to back of the cabinet.

25 Figure 3 is a transverse sectional view showing one of the upper side edge portions and showing particularly the hinge arrangement for the top closure.

Figure 4 shows a corner detail in perspective, the view showing particularly the action of the brace in holding one portion of the 30 top closure in horizontal position.

Figure 5 is a view in perspective of the cob basket which is adapted to seat in the cabinet.

The device includes a pair each of front and rear corner posts 10 and 11. The posts are connected at their upper extremities by the straps 12 and they are also connected by the straps 13, the straps 13 being positioned a sufficient distance from the floor so as to give access to the space beneath the bottom of the cabinet. Each post 10 and 11 is supported on a caster 14, the casters 14 being sufficiently large to facilitate the moving about of the cabinet. Inside the cabinet and extending from the upper front edge to an intermediate point in the floor of the cabinet is an inclined wall 15. The two side walls and the rear wall are in the form of panels 16 which may be made from three-ply veneer or of any other material suitable for taking the desired finish. In a similar manner the space enclosed by the bottom straps 13 is filled by a panel 17. The front of the cabinet proper is thus the inclined wall 15, the cabinet proper being completely enclosed except at the top. In front of the cabinet proper 75 is a prism-shaped space bounded by portions of the bottom and side walls and by the inclined wall 15.

The cobs may be placed directly in the cabinet proper but it is more convenient in every respect that a separate container be provided and made in such dimensions that it seats snugly into the cabinet space. Such a container is shown at 19 in Figure 5. In this instance the container 19 is made from sheet

80 metal which encloses all sides of the container except the top. The container 19 is provided at its sides with bails or other handles 20 for convenience in carrying the container about. Since the top edge of the container 90

19 is substantially on a level with the top edge of the cabinet, it is desirable that the handles 20 be pivotally or otherwise mounted in a manner such that they will not project above the level of the cabinet when the container 19 95 is in place within the cabinet.

The cabinet proper is designed for the storage of corn cobs but the prism-shaped space in front of the cabinet proper affords sufficient room for the storage of many things 100

used around the stove such as shovels, scoops, lid lifters, dust pans, dust cloths and the like. Some of these may rest on the floor of the front compartment but for convenience in placing such things as shovels and dust pans

5 I provide hooks or shelves as shown at 21 in Figure 2.

The storage space in the front of the cabinet is preferably closed by means of a hinged door 22 which hides everything from sight 10 when it is closed but which gives easy access to all of the articles by simply opening the door. The top of the cabinet is also closed for several reasons. The closure in its closed 15 position reduces the amount of dust escaping from the corn cob container and it serves as a convenient table or shelf on which to place utensils and other articles used in the kitchen. In the form of closure which I show there 20 are two leaves 23 each hinged at the side, the two being rabbeted at their inner edges. The hinges 24 are double pin hinges as best shown in Figure 3 so as to afford a movement of the leaf 23 through substantially three quadrants. 25 This makes it possible to hold the leaf 23 in horizontal closed position, in vertical full open position as shown in dotted lines in Figure 3 or in horizontal table leaf position as shown in Figure 4. To maintain the position in Figure 4 the cabinet is provided with 30 braces 25 which are pivotally secured to the front and rear portions 10 and 11 and which are provided at their free ends with notches for engaging the pins 26 projecting from the 35 leaves 23.

Having thus described my invention in such full, clear, and exact terms that its construction and operation will be readily understood by others skilled in the art to which it 40 pertains, what I claim as new and desire to secure by Letters Patent of the United States is:

A two-compartment cabinet having full 45 openings at the top and forward side thereof, hinged closures for the openings, a transversely arranged partition extending from the forward upper edge of said cabinet to a transverse line intermediate the forward and rear edges of the floor of said cabinet and secured to the side walls and the bottom thereof, supporting means secured to the forward side of said partition, and a removable corn cob receptacle shaped and dimensioned to seat 50 within the rear compartment of said cabinet, and secured to the side walls and the bottom thereof, supporting means secured to the forward side of said partition, and a removable corn cob receptacle shaped and dimensioned to seat within the rear compartment of said cabinet, 55 said receptacle being provided with handles on the upper edges of the lateral walls thereof for facilitating the passage of said receptacle into and out of said cabinet through the top opening thereof.

60 In testimony whereof I affix my signature.
HAROLD WARREN TOOL.
